UNITED STATES PATENT OFFICE.

DAVID M. ANDERSON, OF WESTWOOD, NEW JERSEY, ASSIGNOR TO W. F. HESSEL, OF NEW YORK, N. Y.

LAMP HOLDER AND GUARD.

1,314,846.

Specification of Letters Patent. Patented Sept. 2, 1919.

Application filed February 7, 1919. Serial No. 275,656.

To all whom it may concern:

Be it known that I, DAVID M. ANDERSON, a citizen of the United States of America, residing at Westwood, in the county of Bergen and State of New Jersey, have invented certain new and useful Improvements in Lamp Holders and Guards, of which the following is a specification, reference being had therein to the accompanying drawing.

10 This invention comprises a combined lamp holder and guard.

While it is capable of many uses, it is especially adapted as a carrier and protector for incandescent lamps and the like where 15 it is desirable that they may be used in inaccessible places without danger of breakage.

It is contemplated among the objects of the invention to provide a holder and guard, the holder being made preferably of some 20 non-conducting material which will be light and strong and which will constitute a base wherein may be solidly anchored a metallic foundation upon which the guard may be mounted; wherein a lamp may be securely 25 anchored, and provision made to protect the socket and other parts from moisture and the like; whereon a guard may be placed so that it may be readily attached and detached and locked in attached position.

30 It is a further object within the contemplation of the invention to provide a guard, the different components of which are made of light, strong, strain-resisting material, wherein the guard-members are shaped and

35 connected so as to offer a maximum resistance to any pressure which may be exerted against the guard from the outside and in the direction of the lamp; and with which there is associated a means for hanging the 40 lamp and guard as a whole.

Other objects and advantages will in part be apparent and in part be brought out more fully in the description which follows.

Drawings illustrating an embodiment of 45 the invention are hereto annexed, the following views being shown:

Figure 1 is a view in side elevation;

Fig. 2 is a view in longitudinal section;

Fig. 3 is a transverse sectional view on 50 the line 3-3 of Fig. 1;

Fig. 4 is a similar view on the line 4-4 of Fig. 2; and

Fig. 5 is a detailed sectional view of a part.

In these drawings, numeral 1 designates a 55 combined base section and holder, the lower portion of which is formed to constitute a handle or a base upon which it may rest, as desired. The upper portion constitutes an anchorage for a guard and a holder for a 60 lamp. To this end it is provided with a projecting rib portion 2, channeled peripherally to constitute a ledge or the like 3 and bored centrally to comprise a lamp socket holding orifice 4 and an opening for wires. 65 Upon the rib portion 2, there is mounted a guard-holding-member comprising a central section 5 connected with an outer annular section 6, as by ribs 7. In angular relation to the outer peripheral section 6, there is a 70 threaded collar portion or flange 8, as best seen in Fig. 5, which section is provided with openings 9 through which are adapted to pass screws or other securing means 10. These latter constitute a means for holding 75 a lamp socket 11 securely within the orifice 4 and for this purpose the socket may be provided with a groove 12 in which one end of these screws is adapted to seat when in proper position within the flange. The 80 guard-holding member may also be secured upon the socket, as by screws 13 passing through openings 14 disposed in the web portion 7.

Adapted to be associated with the guard-holding member, there is a guard comprising a base portion 15 internally threaded to be associated with the thread on the flange or collar portion 8 of the guard-holding member and upon which base portion there 90 are mounted a plurality of upwardly extending guard members 16. These extend a certain distance in approximate parallelism where they are joined by cross connections 17 in horizontal arrangement, and from this 95 point converge, being joined at their outer extremities when there may be provided a hook or supporting member 18.

The guard herein illustrated is an integral casting as distinguished from devices here- 100

tofore in use wherein the component parts were secured together in various ways as by soldering, clamping or other form of connection. This is a valuable feature of the 5 invention rendering the guard strong and durable and easy to manufacture.

Means are also provided for locking the guard as a whole upon the guard-holding member, and to this end, and as best seen in 10 Fig. 3, the guard-holding member is provided with a depression or groove 19 within which there is adapted to seat a locking screw 20 which is threaded into the base portion 15 of the guard.

15 Within the socket there may be mounted any type of lamp; an incandescent form 22 being here shown.

In the event that it is desired to use the apparatus under water, means are provided 20 for water proofing the parts and in that event the guard holding member shall be constructed with an additional threaded up- 25 standing annular flange 22 arranged upon said guard - holding member 6 to engage corresponding thread upon a water proof inner glass guard or globe 23 which engages a water proofing element 21 positioned between said glass globe and guard-holding member 6. A waterproof connection be- 30 tween the base member 1 and guard-holding member 6 is also effected as by a gasket 25 which extends under the guard-holding member 6. To waterproof the handle at the end where the wires enter, a stuffing box 26 35 is arranged for.

While I have disclosed the invention in the embodiment herein shown, it will be understood that I do not wish to limit myself to the precise form of this disclosure as 40 many changes may be made in the construction and arrangement of the parts without departing from the spirit of the invention or its scope as set forth in the claims.

What I claim is:—

45 1. A combined holder and guard for lamps and the like comprising a base portion having a handle and provided with a bore, a guard-holding member disposed on said base portion, a threaded collar disposed 50 on said guard-holding member, means passing through said collar and said base portion for securing a lamp socket within the bore; a socket secured within the bore by said means, a guard member having a 55 threaded base portion associated with said threaded flange, guard members extending upwardly from said base portion in approximate parallelism and then converging and joined at their point of contact, a hook member 60 secured to said guard members at their points of connection, horizontally-disposed members connecting said guard members, and means for locking the base portion to said flanged portion when said base and

65 flange are associated to connect the guard to the guard-holding member.

2. A combined holder and guard for lamps and the like comprising a base portion having a handle and provided with a bore, a 70 guard-holding member disposed on said base portion, a threaded collar disposed on said guard-holding member, means passing through said collar and said base member for securing a lamp socket within the bore; a socket secured within the bore by said 75 means, a guard member having a threaded base portion associated with said threaded flange, guard members extending upwardly from said base portion in approximate parallelism and then converging and joined at 80 their point of contact, a hook member secured to said guard members at their points of connection, horizontally-disposed members connecting said guard members, and 85 means for locking the base portion to said flanged portion when said base and flange are associated to connect the guard to the guard-holding member, said guard-holding member comprising an inner member surrounding said bore, web members connecting these portions, and a threaded flange in 90 annular relation to the outer member.

3. A combined holder and guard for lamps and the like comprising a base portion having a handle and provided with a bore, a 95 guard-holding member disposed on said base portion, a threaded collar disposed on said guard - holding member, means passing through said collar and said base member for securing a lamp socket within the bore; a socket secured within the bore by said 100 means, a guard member having a threaded base portion associated with said threaded flange, guard members extending upwardly from said base portion in approximate parallelism and then converging and joined at 105 their point of contact, a hook member secured to said guard members at their points of connection, horizontally-disposed members connecting said guard members, means for locking the base-portion to said flanged portion when said base and flange are associated to connect the guard to the socket, 110 said guard-holding member comprising an inner member surrounding said bore, web members connecting these portions, a threaded flange in annular relation to the outer member, and means for securing the 115 guard-holding member to the guard, said means comprising openings disposed in the web portion through which securing elements are adapted to pass.

4. A combined holder and guard for lamps and the like comprising a base portion having a flange and provided with a 125 bore, a guard-holding member disposed on said base portion, a collar disposed on said guard - holding member, means passing

through said collar and said base portion for securing a lamp socket within the bore, a guard member having a base portion associated with said flange, guard members extending upwardly from said base portion, and means for locking the base portion to said flanged portion when said base and

flange are associated to connect the guard to the guard-holding member.

In testimony whereof I affix my signature in presence of a witness.

DAVID M. ANDERSON.
